RECEPTACLE FOR ARTIFICIAL TEETH

Daniel Wachtel, Long Island City, N.Y.

Application March 27, 1959, Serial No. 55,208

Term of patent 14 years

(Cl. D58—11)

FIG. 1

FIG. 2

FIG. 3

Figure 1 is an upper front perspective view of a receptacle for artificial teeth embodying my new design;

Figure 2 is a lower rear perspective view thereof; and

Figure 3 is a cross-sectional view thereof taken along the transverse midplane.

I claim:

The ornamental design for a receptacle for artificial teeth, substantially as shown.
